INVENTOR
Mark Lavitt
by
Arthur E. Jenkins,
ATTORNEY

UNITED STATES PATENT OFFICE.

MAX LAVITT, OF ELLINGTON, CONNECTICUT.

TOBACCO LATH.

Application filed May 21, 1925. Serial No. 31,918.

My invention relates to the class of devices that are employed for the purpose of hanging tobacco after being cut and taken from the stalk, and an object of the invention, among others, is the production of a type of tobacco lath that may be produced at a minimum cost, that shall be durable, and one from which tobacco may be removed in an expeditious manner.

10 One form of device embodying my invention and in the construction and use of which the objects herein set out, as well as others, may be attained, is illustrated in the accompanying drawings, in which—

15 Figure 1 is a face view of a tobacco lath embodying my invention.

Figure 2 is an edge view of the same.

Figure 3 is a view in cross section through the lath.

20 As is well known, tobacco, after being cut, is hung in tobacco sheds or similar buildings for the purpose of drying, a common method being to suspend the tobacco by means of laths to which the tobacco is secured, the ends of the laths being placed upon cross pieces supported at suitable intervals upon beams of the building, or upon beams placed for such support. A common method employed for drying at the present time, is to suspend each leaf by its stem separately from other leaves, as distinguished from suspending the leaves upon an entire stalk, and this method of single leaf suspension requires a very large number of laths, running into hundreds of thousands in plantations of not uncommon size, and as the laths under the conditions of use soon become broken and otherwise useless, thereby necessitating their replacement,

25 it is of vital importance that they be produced at a very low cost. My invention illustrated and described herein accomplishes this purpose and enables the laths not only to be produced at a minimum cost, but in addition a lath is provided from which the tobacco may be very readily removed and in a very expeditious manner, and this is a very material consideration as it reduces the cost of handling the tobacco after it has been hung, and it also

reduces the liability to injury of the tobacco when it is being removed from the laths.

In carrying my invention into effect I take a lath 10, that is composed of any suitable material, as wood, having the desired characteristics, and to this lath I secure a number of hooks 11 projecting preferably from one of the widest faces of the lath, these hooks being all extended in the same direction and preferably in line lengthwise of the lath, and as shown in Figure 1 of the drawings. In the preferred form of construction these hooks are arranged in pairs, the members of each pair being formed at the ends of branches 12 of U-shaped pieces of metal in the form of staples 13, said branches being forced through the material of the lath and the ends being then bent into the form of hooks that are spaced a sufficient distance from the surface of the lath to enable the stems 14 of the tobacco leaves 15 to be readily placed upon the hooks without interference by the lath, in this operation the stems being pierced by the hooks.

By the use of laths thus constructed the tobacco may be readily placed thereon with little liability to injury of the leaves, and a further and material advantage resides in the removal of the leaves, which operation may be quickly accomplished by a sweeping action of the hand lengthwise along the lath from one end to the other, thereby rapidly removing all of the leaves from a lath with little liability of injury to the leaves in such removal.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim—

1. A tobacco lath comprising a body with staples projecting therethrough and having branches each formed in a hook, said

hooks being spaced from said body to receive the ends of the stems of tobacco leaves between the hooks and said body.

2. A tobacco lath comprising a body with staples projecting therefrom and having branches each formed into a hook, said hooks being all extended in the same direction lengthwise of the lath.

3. A tobacco lath comprising a body with staples each having its branches projected through the lath from one side to the other and extending therefrom on the opposite side, said extensions being formed into hooks all projecting in the same direction lengthwise of the lath.

MAX LAVITT.
